UNITED STATES PATENT OFFICE.

ELINOR C. WALSH, OF HELENA, MONTANA.

SANITARY DRINKING-CUP.

1,221,639.

Specification of Letters Patent.

Patented Apr. 3, 1917.

Application filed May 2, 1913. Serial No. 765,094.

To all whom it may concern:

Be it known that I, ELINOR C. WALSH, a citizen of the United States, residing at Helena, in the county of Lewis and Clark 5 and State of Montana, have invented certain new and useful Improvements in Sanitary Drinking-Cups; and I do hereby declare the following to be a full, clear, and exact description of the invention, such as 10 will enable others skilled in the art to which it appertains to make and use the same.

My invention relates to an improved sanitary drinking cup, and it consists in the constructions herein described and claimed.

15 An object of my invention is to provide an improved sanitary metal drinking cup formed throughout with smooth polished surfaces, and entirely free from all crevices, and abrupt angles or joints to afford favorable 20 locations for the lodgment and retention of germs or other foreign substances. The chief requirement of this cup, in its construction, is an absolutely smooth, even surface, both inside and out, having no 25 beads, sharp depressions, angles, or lines, but with full curves where such depressions, angles, or lines usually occur in the ordinary drinking cup, or other vessel. The various handles shown and described must 30 conform to this requirement.

A further object of my invention is to provide an attractive and inexpensive cup, which is light and strong in construction and thoroughly sanitary in use.

35 In the accompanying drawings, forming a part of this application and in which similar reference symbols indicate corresponding parts in the several views:—

Figure 1 is a perspective view of a sanitary 40 drinking cup illustrating one embodiment of my invention;

Fig. 2 is an enlarged central section on the line 2—2 of Fig. 1;

Fig. 3 is a central section, showing the 45 cup at a stage in its manufacture before the integral strip for forming the handle has been bent to its final shape;

Fig. 4 is a detail section on the line 4—4 of Fig. 2;

50 Fig. 5 is a fragmentary section illustrating a slightly modified form of handle;

Fig. 6 illustrates a modified construction; and

55 Fig. 7 is a section on the line 7—7 of Fig. 6.

Figs. 1—4 of the drawings illustrate a sani-

tary metal drinking cup formed throughout with smooth polished surfaces, and comprising a cylindrical side wall 1 and a flat base 2 connected by an annular rounded 60 edge 3. The cup is spun, stamped, cast, or otherwise formed of a single integral piece of any suitable alloy or metal, such as silver or aluminum.

An integral handle 4 extends from the 65 cylindrical side wall 1 of the cup in a curved plane merging smoothly into said side wall, as shown at 5; the junction between the edges of said handle and the top edge of said cylindrical side wall being rounded at 70 6 to avoid the formation of a sharp corner or abrupt bend at such point. The lower end of the handle 4 is firmly attached to the cylindrical side wall 1 of the cup by a connection 7 which is curved to merge 75 smoothly into the surfaces of said side wall and handle, as shown especially in Figs. 1, 2 and 4; said connection 7 being advantageously formed by soldering, casting, or molding, or by a wiped joint. I have shown 80 the handle 4 provided with an aperture 8 for insuring a strong and positive connection between said handle and the material of the connection 7.

Fig. 5 shows a slight modification in 85 which the cup is formed with an integral handle in the manner just described, and the lower end of the handle 9 is spaced from and unattached to the cylindrical side wall 10 of the cup. 90

Figs. 6 and 7 illustrate an advantageous construction, in which a cup is formed in the previously described manner, and a metal reinforcing disk 11 is brazed or otherwise rigidly attached to the outer face of the flat cup base 12; said reinforcing disk having the same diameter as the flat base and having its peripheral edge 13 inclined or rounded to extend flush with the outer face of the annular rounded edge portion 14 of the cup. 100 A handle 15 is formed integral with the metal reinforcing disk 11 and curved with its upper end 16 spaced from and unattached to the cylindrical side wall 17 of the cup; a curved filling 18 of solder or other suitable material being secured at the junction of said handle and cup and shaped to merge smoothly into the surfaces of said elements for preventing the formation of a sharp corner or abrupt bend at such point. 105

In this advantageous construction, the flat base 12 is strongly reinforced by the metal

disk 11 and constitutes a rigid support for the stiff arched annular portion 14 of the cup; thereby insuring a maximum rigidity and strength with a minimum weight. This 5 provides a strong and durable construction in which the cup with its contents is supported directly by the reinforcing disk 11 on the lower end of the handle 15; said handle being provided with a free upper end 10 spaced from the top edge of the cup and acting positively to prevent the user's hand from coming into contact with said edge of the cup.

This bottom plate carrying the handle 15 serves not only to stiffen the bottom of the cup where the wear is the greatest, and to provide a plate of sufficient stiffness for a handle, which preferably should not be connected at its upper end with the body of the 20 cup; but also serves as a weight applied to the bottom of the cup, and thus serves to lower the center of gravity of the cup, and to thus render it less liable to be upset, or when tilted will tend to return the cup to 25 the upright position.

By this construction an extremely light metal body may be imparted to the cup, and a stiffening plate may be applied to the bottom which serves also to provide a stiff tail 30 piece for the handle.

It will be noted that with this form of construction there is absolutely an unbroken circular outer rim of the cup, and the hand of the user, grasping the handle, will not 35 touch anywhere near the rim of the cup.

From the above description it will be clear that my invention provides an attractive and inexpensive drinking cup formed throughout with smooth polished surfaces, which 40 will be thoroughly sanitary in use.

I have illustrated and described preferred and satisfactory constructions, but changes could be made within the spirit and scope of my invention.

45 I claim:—

1. As a new article of manufacture a sanitary drinking cup having its body portion formed of a single integral piece of metal provided with a flat bottom and rounded curves 50 connecting said bottom with the side walls,

and with a handle integral with and projecting from the said cup, the surfaces of the handle and the body of the cup merging into each other in curved lines, whereby a cup with a smooth surface is formed without crevices 55 or other dirt-receiving cavities.

2. As a new article of manufacture, a sanitary drinking cup having its body portion formed of a single integral piece of metal shaped with rounded curves to provide 60 curved side walls terminating in a flat base, a reinforcing disk of slightly less diameter than said flat base rigidly attached on the outer face of the latter having its peripheral edge inclined to extend flush with the outer 65 face of said annular rounded edge portion, a curved handle formed integral with said reinforcing disk, and curved connections between said handle and cup merging smoothly into the plane of both, the whole cup being 70 free from any sharp depressions, angles, or corners, adapted to collect dirt, grease, or other adherent matter, substantially as described.

3. As a new article of manufacture, a sanitary drinking cup formed of a single integral piece of thin metal shaped with rounded curves on the side, terminating in a flat bottom, and a reinforcing disk of heavier metal secured to said flat bottom and having 80 its peripheral edge shaped to form a smooth surface with the exterior of said flat bottom, the said reinforcing disk being provided with a laterally-projecting lug bent to form 85 a curved handle, the upper end of which is 90 spaced apart from the side wall of the cup, and the angle of divergence between the handle and the cup being filled in with non-absorbent material, and shaped in a rounded curve, the whole cup being free from any 95 sharp depressions, angles, or corners, adapted to collect dirt, grease, or other adherent matter, substantially as described.

In testimony whereof I affix my signature, in presence of two witnesses.

ELINOR C. WALSH.
